UNITED STATES PATENT OFFICE.

ROBERT P. GREENLEAF, OF CLEVELAND, OHIO, ASSIGNOR TO FRANK BILLINGS.

LOADING MACHINE.

Application filed January 17, 1917. Serial No. 142,789.

To all whom it may concern:

Be it known that I, ROBERT P. GREENLEAF, a citizen of the United States, residing at Cleveland, in the county of Cuyahoga and State of Ohio, have invented a certain new and useful Improvement in Loading Machines, of which the following is a full, clear, and exact description.

The present invention relates to a loading machine adapted particularly for use in mines wherein the permissible head room is limited, and wherein the passageway or drift in which the machine is working is such that it is necessary in order to load the material into a car or receiving element at the rear of the machine that the material either be brought through or over the machine from a point in front thereof into the receiving element.

20 The object of the present invention is to provide a loading machine including a digging and scooping element preferably in the form of a shovel or bucket, which after receiving a load, carries the material back over the machine and dumps it into the receiving element behind the machine. Further it is the aim of the invention to accomplish this result without the necessity for cables, trolley or cumbersome supporting 25 and carrying mechanism, and to support the bucket, shovel or digging element so that it will have a fairly long thrust or stroke, and in swinging back over the machine to dump the material, will not project above 30 the floor or mine track such a distance that it might strike the upper wall of the passageway in which the machine is being worked, or the overhead mine timbering. Additional objects are to give the digging 35 member with a single motor the movements necessary to dig or pick up a load, to carry the material rearwardly and to discharge it behind the machine, and to provide means whereby the length of the forward or digging 40 stroke can be varied without varying the dumping point or rearward limit of movement.

Still further the invention aims to provide a machine having the above characteristics and desirable features and which is at the same time not complicated in construction, durable, and which works continuously or automatically, the digging and conveying element passing without interruption 45 through one cycle of movement after another until the motor is stopped.

The above and additional objects are accomplished by my invention which may be briefly summarized as consisting in certain novel details of construction and combinations and arrangements of parts which will be described in the specification and set forth in the appended claims.

In the accompanying sheet of drawings wherein I have shown one embodiment of my invention which works with high efficiency, Fig. 1 is a side elevation of the machine with the shovel shown in full lines in one position, while it is being moved rearwardly over the machine to the dumping point, the shovel being shown by dotted lines in other positions which it assumes in passing from one complete path or cycle of movement; Fig. 2 is a similar view of the forward part of the machine showing the shovel in different positions by full and dotted lines, the full line position indicating the shovel near the beginning of the digging or filling stroke; Fig. 3 is a top plan view with parts in section; Fig. 4 is a perspective view of a block which is adjustable in a slotted link to vary the stroke of the shovel; and Fig. 5 is a fragmentary elevation showing the block of Fig. 4 adjusted to a different position than shown in Figs. 1 and 2.

The machine in which my invention is embodied is preferably run upon a track 10 which may be a track laid on the floor of a mine. The machine includes a truck frame 11, having track wheels 12, the middle portion of the frame 11 being depressed to accommodate certain moving parts to be referred to later. Supported by the frame 11 is a body or housing 13 which is pivoted at 15 the rear part of the frame or truck frame 11, by a vertical king bolt 14 so that it may be turned about a vertical axis to enable the shovel to reach material located not only directly in front but within a given distance 20 to either side of the machine. The forward part of the body 13 is provided with one or more rollers 15 designed to run upon an arc-shaped track 16, concentric with respect to the axis of the king bolt 14. Supported on 25 the rear part of the body 13 is a motor 17, having a forwardly extending shaft 18, which through suitable gearing here shown as worm wheel gearing 19, rotates a shaft 20 supported in bearings 21 at the top of two 30 upstanding side walls 22 of the body or housing 13. These side walls 22 not only

support the shaft 20, but they also indirectly support the shovel and other parts, and their upper edges are designed to be engaged by rollers carried by certain of the shovel supporting arms, the forward portions of these side walls being curved on arcs of a circle of given radius, and then inclined downwardly rearwardly in straight lines as will be seen particularly from Figs. 1 and 2. Secured to the shaft 20 are a pair of crank arms 23 which are just outside of the side walls 22 of the housing. It is through the rotation of these cranks operated by the single motor 17 that the shovel is given the digging and conveying movement necessary to pick up material in front of the machine and deposit it into a car or other receiving member at the rear of the machine, a portion of a car being shown at 24 in Fig. 1.

20 The material is picked up by a shovel or bucket 25 which is open at the front and has sides, bottom, and rear walls. This shovel is secured to two arms 26, constituting a part of a foldable and extensible support, these arms extending along the bottom portion of the shovel and then outwardly therefrom, the portion of the arms extending from the shovel being at an angle to the parts which extend along the bottom thereof. Pivoted connected at 27 to the free ends of the arms 26 are a pair of arms 28, the lower or inner ends of which are pivotally connected to the ends of a shaft 29 journaled in the forward portions of the walls 22 of the housing.

30 Connected at 30 to the arms 26, a short distance below the pivoted points 27, are arms 31, which at their lower ends are pivotally connected at 32 to relatively short arms 33, likewise connected to the ends of shaft 29. The arms 26, 28, 31 and 33 constitute supporting and operating mechanism for the shovel; these arms being arranged in two sets of four arms each which approximate a parallelogram. While the arms as here shown are not in the form of a true parallelogram, inasmuch as opposite arms or the portions thereof between the pivot points 27, 29, 30 and 32 are not precisely the same length and therefore parallel, nevertheless these sets of arms perform the function substantially of parallel movement mechanism.

35 For the purpose of transmitting movement between the rotating shaft 20 and the shovel supporting and operating arms just described, I employ two curved links 34 which are pivotally connected at 35 to the ends of the cranks 23, and at or near their outer ends are connected to the arms 31.

40 A straight pivotal connection between the links 34 and the arms 31 would suffice if strokes of constant length were to be given to the shovel, but inasmuch as it is one of the features of this invention that the forward or digging strokes may be varied, I

provide means for adjusting the effective lengths of the links or the effective points of connection between these links and the arms 31. As will be apparent from the drawings, during the complete cycle of movement of the shovel and of the collapsible and extensible shovel support, the links 34 act at times as tension members and at other times as compression members. It will be apparent also that while the shovel is being given its filling thrust or movement, the links 34 acting on the arms 31 push the shovel forwardly and therefore act as compression members and while the shovel is being moved rearwardly over the machine to the dumping point these links are acting as tension members. The varying of the length of the filling stroke of the shovel without varying the rearward limit of movement of the shovel is brought about by varying the effective lengths of the links while acting as compression members so as to vary the distance that the shovel is moved forwardly during the filling stroke while still allowing the normal or maximum effective length of the links during the period of time that these links act as tension members, and particularly while they serve to move the shovel to the dumping point. In carrying out this feature of the invention I provide in the links elongated slots 36 which receive adjustable blocks or abutments 37 adapted to be fixed in or adjusted to different positions in the slots, and also receive square bushings 38 which are designed to slide back and forth between these blocks 37 and the outer ends of the slots when the links change from compression members to tension members and vice versa. Passing through these bushings 38 is a cross shaft 39, the ends of which pass freely through the ends of the arms 31.

45 For the purpose of providing means for adjusting the position of the blocks in the slots 36, the forward slotted ends of these links are provided with brackets or extensions 40 in which are journaled threaded shafts 41 which extend through and are engaged by nuts 42 constituting extensions of the blocks 37. The outer ends of the links 34 are provided also with bracket-like extensions 43 having bearing bosses at their free ends in which is journaled a cross-shaft 44, see particularly Fig. 3, to the middle of which is secured an adjusting hand wheel 45. The ends of this shaft 43 are connected by bevel gearing 46 to the threaded screws or shafts 41 which are engaged by the slide blocks 37.

50 If this hand wheel 44 is turned in one direction or the other, the blocks will be moved equal amounts along the slots 36. As these blocks or abutments are engaged by the bushings 38 when the links are acting as compression members, it will be ap-

parent that the farther these blocks are moved inwardly along the slots the shorter the length of the filling stroke will be, and as the blocks are moved toward the outer 5 ends of the slots the length of the filling stroke will be increased, for this adjustment has the effect of increasing the distance that the shovel is pushed forwardly by the links during the filling stroke. In Figs. 1 and 2 10 the blocks are adjusted for the maximum filling stroke, the bushings then being fixed between the abutments and the outer ends of the links.

The cross-shaft 38^a extending between the 15 blocks 37 is provided with rollers 46 which, while the shovel is being moved over the machine from substantially the position shown in Fig. 1 to substantially the position shown by the extreme right-hand dotted 20 position of the shovel, are designed to travel over and to be guided by the curved or peculiarly shaped upper edges of the side walls 22, so that the shovel in passing rearwardly and forwardly over the machine will 25 travel through the desired path and at the desired height from the mine floor. Not only do these rollers engage the guides formed by the side walls 22 during the to and fro movement of the shovel over the machine, 30 but throughout the digging or material receiving portion of the movement of the shovel these rollers engage a pair of guides 47 whose function is to control the path of movement of the lower digging edge of the 35 shovel while it is being filled with material. Preferably these guides 47 which are supported at the front part of the body or housing 13 are adjustable so that the lower edge of the shovel can be caused to pass through 40 any desired plane, or a path having any desired angular relation to the ground or floor from which the material is scraped by the shovel. As here shown, these guides 47 are positioned so that throughout the material receiving portion of the stroke of the shovel 45 the lower edge of the same moves horizontally or through a plane parallel with the plane of the track 10. In order that these guides may be readily adjusted, they are supported by bolts 48 pivoted to the guides at 49, and passing through swinging blocks 55 pivotally mounted between webs 56 at the forward end of the body or housing 13. Nuts 51 which engage threaded portions of 50 the supporting bolts 48 and which rest upon the tops or upper ends of the trunnioned blocks 55 are adapted to be turned to raise or lower the bolts 48 and hence to adjust either the forward or rear ends or both of 55 the guides 47.

With the shovel supporting and operating mechanism as described, (including the four pivotally connected arms pivoted to the housing and one of the arms having a 60 link connection with the rotating crank of

the motor, and by certain timely and peculiar guiding actions afforded by the lower edges of the curved links 34, the upper edges of the side walls of the housing and the guide members 47) during one complete rotation of the cranks the shovel is given a certain length of digging movement by being moved forwardly and tipped as it is moved with the digging edge moving in a predetermined plane determined by the angularity or positions of the guides 47, which during this portion of the shovel movement are engaged by the rollers 46. It will be observed that at the start of this digging thrust or movement the shovel support is collapsed so to speak, the arms 26, 28 and 31 being as near parallelism as the form of the support will admit, and that as the cranks are rotated downward from the position shown in Fig. 2 (the cranks 23 operating in a counter-clockwise direction as viewed in this figure) the support for the shovel is extended, that is to say, the arms 26 and the arms 28 are gradually caused to approach alignment. This enables a forward filling stroke or thrust of considerable length to be obtained, the precise length of this portion of the stroke depending upon the position of the blocks 37 in the slots of the connecting and operating links 34. When the cranks 23 and links 34 are in alignment, that is to say, when the axis of the shaft 20, the axis of the pivotal connection 35 and the axis of the shaft 38^a which virtually connect the arms 31 to the slotted links 34, are on a dead center, the shovel is at the forward or outward end or limit of its movement. Following the end of the forward thrust or movement which fills the shovel, the latter 100 is elevated so as to prevent it moving rearwardly along the same path that it traversed during the filling portion of the stroke and so as to prevent the material discharging prematurely from the shovel. This takes 105 place when the cranks 23 swing downwardly for a certain distance beyond the dead center and is accomplished by the engagement and sliding action of the slotted links 34 with rollers 60 mounted loosely on 110 the shaft 29 by which the arms 28 and 33 are connected to the side walls of the housing. As the movement of the cranks 23 continues downward and rearward the curved links 34 slide or roll on these rollers, 115 and the effect of this is to fold or collapse the arms of the support and to move the same and the shovel rearwardly over the machine as the same is shown in full lines in Fig. 1, the long arms 26 which are directly connected to the shovel being as here shown, folded or swung back against the bosses at the ends of the arms 33 connected to the lower ends of the arms 31. At or about this point the sliding or rolling ac- 120

tion of the slotted links 34 on the rollers 60 ceases, and at or about this time the rollers 46 on the shaft 38 engage the curved upper surfaces or edges of the side walls 22 whereupon the shovel and the four arms of the shovel support swing downwardly as a unit, the rollers 46 rolling down the curved portions of the edges of the walls 22 and then as these rollers travel along 10 the straight portions of the upper edges of these walls, the shovel is swung rearwardly and its load is discharged into the car or receiving element 24 at the rear of the machine as shown by the right-hand dotted 15 line position of the shovel and arms 26 in Fig. 1, the ends of the arms 26 which are connected to the ends of the arms 28 now being near the bottom of the machine. In other words, during the movement from 20 the full line position of Fig. 2 to the dotted line position of Fig. 1, the shovel has been moved forwardly so as to be filled, is then elevated and moved rearwardly, undergoing a gradual turning or rotating movement of 25 more than 180°. The continued rotation of the cranks now returns the shovel and its supporting arms, moving them forwardly to the full line position shown in Fig. 1. During the early part of the return or forward movement the parts pass through the 30 same path that they traversed during the latter part of the rearward movement, but when the rollers 46 reach the ends of the curved portions of the edges of the housing 35 walls 22 with the arms of the shovel support collapsed or folded together as in Fig. 1, the four arms of the support now swing as a unit about the axis of shaft 29 from substantially the full line position shown in 40 Fig. 1 to substantially the full line position shown in Fig. 2, or until the rollers engage the inclined guides 47 at the start of the forward digging or filling thrust.

It will be understood that the shovel and 45 the parts supporting and operating it pass through the cycle of movement just described, smoothly and continuously, and that as the cranks rotate through one revolution after the other, one complete cycle of 50 movement after the other is given to the shovel and the parts which support and operate it, the material being scooped up into the shovel and then carried back and dumped into the car, shovelful after shovelful being 55 discharged into the car without any attention on the part of the operator. As the material is picked up in front of the machine it will be moved forwardly to additional material, but ordinarily a large number of 60 complete shoveling and loading strokes can be given to the moving mechanism without the necessity for moving the machine forwardly. The operator can swing the super- 65 structure mounted on the truck frame about the axis of the king bolt so that the shovel

will be able to load the material located on both sides of the longitudinal center line of the machine. No swinging mechanism is shown, it being understood that the machine is sufficiently light in weight that the operator can with a suitable crow-bar or other tool turn the moving mechanism about the axis of the king bolt 14 in either direction as he chooses and as far as necessary. To vary the depth of digging the operator has simply 70 to vary the height and inclination of the guides 47 by turning the nuts 57, and to vary the length of the digging stroke the operator turns the hand-wheel 44 in one direction or another, depending upon whether 75 conditions require that the filling stroke be increased or decreased. This, as before stated, does not vary the position of the shovel when it discharges the material into 80 the car.

While the shovel is being filled, there is, of course, a rearward thrust imparted to the digging machine, and to prevent any rearward movement as the shovel is being moved forwardly and filled, I provide a pair of rail grips, each in this case consisting of a pair of toothed volute curved members 65, each pair mounted on the lower ends of studs 66 on opposite sides of a rail of the track and adapted to be turned so as to grip the rail by a spring 67 extending between arms 68 at the upper ends of the studs 66. These pivoted members are carried by a substantially horizontal plate 69 pivoted at 70 on the lower rear end of the machine directly above the track rail so that the rail gripper may be swung to rail engaging position as shown in Figs. 1 and 3, or may be elevated to inoperative position as when it is desired to move the machine a distance along the 75 mine track.

With these rail grips, any tendency to back the machine causes the toothed plates to more tightly grip the rail, and any force tending to move the machine forwardly 110 causes the toothed plates to release the rail so as to permit such forward movement, the toothed plates 65 having their toothed edges so curved that this action takes place.

Having thus described my invention, what 115 I claim is:

1. In a loading machine, a frame, a shovel, and means for causing the shovel to be positively and substantially continuously moved through a fixed cycle of predetermined filling and dumping movements including a filling movement at the front of the frame and a movement of translation back toward and over the machine to discharge the material at the rear of the machine and a return movement to the front of the machine for the start of the next succeeding cycle.

2. In a loading machine, a frame, a shovel, means for causing the shovel to be positively and substantially continuously moved 125

through a fixed cycle of predetermined filling and dumping movements including a filling movement at the front of the frame and a movement of translation back toward and over the machine to dumping position which is such that the material is discharged by the shovel at the rear of the machine and a return movement to the front of the machine for the start of the next succeeding cycle, and means whereby the cycle may be varied by modifying the extent of the filling movement without materially changing the dumping point.

3. In a loading machine, a frame, a shovel, shovel supporting arms with power means connected to the shovel supporting arms for causing the shovel to be positively and substantially continuously moved throughout a fixed cycle of predetermined movements including a filling movement at the front of the frame, a movement of translation back toward and over the machine to dumping position which is such that the material is discharged by the shovel at the rear of the machine, and a return movement for the start of the next cycle.

4. In a loading machine, a frame, a shovel, shovel supporting arms with power means for causing the shovel to be positively and substantially continuously moved throughout a fixed cycle of predetermined movements including a filling movement at the front of the frame, a movement of translation back toward and over the machine to dumping position which is such that the material is discharged by the shovel at the rear of the machine, and a return movement for the start of the next cycle, said power mechanism including a continuously operating motor, and members connecting it to the shovel supporting arms.

5. In a loading machine, a frame or base, a shovel, means comprising a plurality of connected arms connecting the shovel to the frame or base, and means comprising a motor, a crank rotated by the motor and having a link connection with one of said arms for causing the shovel to have a forward filling thrust or movement and then to be elevated and moved rearwardly over the machine so as to deposit the material carried thereby behind the machine.

6. In a loading machine, a frame or base, a shovel, means comprising a plurality of connected arms connecting the shovel to the frame or base and constituting a collapsible and extensible shovel support, means com-

prising a motor, a crank rotated by the motor and a link connected to the crank and to one of said arms for causing the shovel to have a forward filling thrust or movement and then to be elevated and moved rearwardly over the machine so as to deposit the material carried thereby behind the machine, and means whereby the effective length of the link may be varied to vary the length of the filling stroke of the shovel.

7. In a loading machine, a frame or base, a shovel, means comprising a plurality of connected arms connecting the shovel to the frame or base, means comprising a motor, a crank rotated thereby and a link connecting the crank to one of said arms for causing the shovel to be given a cycle of movement which fills the shovel and causes the shovel to later deposit the material at the rear of the machine, and a guide with which said link co-operates during a portion of the movement of the link.

8. In a loading machine, a frame or base, a shovel, means comprising a plurality of connected arms connecting the shovel to the frame or base and constituting a collapsible and extensible shovel support, means comprising a motor, a crank rotated by the motor and a link connected to the crank and to one of said arms for causing the shovel to have a forward filling thrust or movement and then to be elevated and moved rearwardly over the machine so as to deposit the material carried thereby behind the machine, said frame or base having a guide with which a portion of said shovel support co-operates during a portion of the movement of said support.

9. In a loading machine, a frame or base, a shovel, means comprising a plurality of connected arms connecting the shovel to the frame or base and constituting a collapsible and extensible shovel support, means comprising a motor, a crank rotated by the motor and a link connected to the crank and to one of said arms for causing the shovel to have a forward filling thrust or movement and then to be elevated and moved rearwardly over the machine so as to deposit the material carried thereby behind the machine, and guides which are engaged by the links and by said shovel support during portions of the movement of the shovel.

In testimony whereof, I hereunto affix my signature.

ROBERT P. GREENLEAF.
